UNITED STATES PATENT OFFICE.

FERRUCCIO COSSUTTA, OF TRIESTE, ITALY.

HULL CONSTRUCTION FOR SUBMARINE AND LIKE VESSELS.

Application filed January 10, 1921. Serial No. 436,348.

(GRANTED UNDER THE PROVISIONS OF THE ACT OF MARCH 3, 1921, 41 STAT. L., 1313.)

To all whom it may concern:

Be it known that I, FERRUCCIO COSSUTTA, a subject of the King of Italy, residing at Trieste, in the Kingdom of Italy, have invented new and useful Improvements in Hull Construction for Submarine and Like Vessels (for which I have filed applications in Austria April 25, 1916; in Hungary May 12, 1916, Patent No. 7,249; and in Germany, 10 May 15, 1916), of which the following is a specification.

This invention relates to hull construction of submarine and like vessels.

Heretofore designers of submarines have 15 employed almost exclusively the circular form for the cross section of that part of the hull which has to stand the pressure of the water.

The reason why the circular shape is 20 practically essential is that hulls of other shape of cross section require too heavy scantlings to attain the necessary strength of resistance. However, from the point of view of stability and seaworthiness the circular form is far from desirable. For instance, the distribution of the equipment is disadvantageous with a circular shape and as a consequence the conditions for stability are far from being satisfactory; the equipment which is heavy and occupies much 25 space has to be raised towards the centre of the hull, the lower part of it being too restricted, and as a consequence of the centre of gravity being comparatively high the arrangement becomes detrimental to stability and it is necessary to employ ballast in 30 order to obtain minimum seagoing qualities.

The present invention has as one object 35 the solution of these problems, i. e. to obtain a hull which does not require a greater quantity of material than one of circular shape while permitting of a more convenient distribution of weights and providing sufficient stability without the necessity of 40 using ballast.

In the drawing accompanying this specification a preferred form of hull cross section according to the invention is illustrated. The figure shows the sections of the inner 45 or resistant and of the outer or not resistant hull of a submarine. The section of the inner hull which has to resist the pressure of submersion, and which forms the object

of the present application, is composed by two arcs of a circle or of a geometrical form 55 which slightly differs from the circular form, and which intersect each other approximately at the bilge.

The upper arc (a) has a greater curvature than the lower arc (b). 60

The pressure proportional to immersion on the superior arc tends to produce a deformation by elongation in the sense of the vertical axis and to diminish the distance between the two points of intersection with 65 the lower arc. The lower arc, on the contrary, by effect of the pressure, tends to become deformed in such a manner as to separate the said two points of intersection, and these deformations of the two arcs partly 70 compensate each other.

Calculations carried out with the utmost precision prove that in the form of section described the bending moment on the top of the upper arc is smaller than that 75 on a purely circular section of equal area.

In order to obtain the due resistance of the lower arc certainly a greater quantity of material is required than if the section were wholly circular. However, the usual 80 structures for the bedding of motors, batteries, etc., form such a stiffening that extra increase of material and consequently of weight can be dispensed with.

The weight of a hull built after this manner is not superior to that of a vessel of circular section of equal area or else equal displacement, but the advantages of the former with regard to the distribution of the installations, are obvious. With equal 85 areas of cross section the horse-shoe section of the invention is much larger in periphery than a circular section, and the bilge of the hull is formed by the arc of a larger circle whereby the equipment which requires great space, such as internal combustion engines, electrical motors, electrical batteries, etc., can be placed much nearer to the bottom than in the case of a circular section. 90

This advantage has as a consequence the attainment of a sufficient amount of absolute stability when diving, doing away entirely with the dead weight of ballast which is indispensable in the case of a submarine 105 of circular section.

This saving of weight is available for the inner hull the lower arc be less bent than an increase of seagoing and military qualities of the boat.

Also with regard to the shape of the external hull considerable advantages are secured by employing the horse-shoe-section.

The wall of the outer hull (c) begins at the intersecting point of the two arcs which form the inner hull and the wall (c) can 10 run into the wall (b) in a smooth curve, thus insuring continuity, which, in the case of a circular inner hull, cannot be attained.

The superior part of the outer hull (d) forming the submarine's deck can be made 15 nearly flat, the whole forming a continuous surface and therefore favorable to the behaviour of the hull when navigating on the surface and in diving acting much like a torpedo, which it resembles in form.

20 It is of importance that in the section of

the inner hull the lower arc be less bent than the upper arc.

I claim:

1. A hull construction for submarine and like vessels in which a transverse section of 25 that part of the hull which resists the external pressure consist of two elastic arcs of different radii of curvature both concave towards the interior, and intersecting each other at two points substantially at the level 30 of the bilge, the arc of greater radius forming the bottom and the arc of less radius the top and sides, of said section.

2. A hull construction for submarines after claim 1 comprising an outer hull structure 35 the form of which in cross-section has a curved portion forming a continuous curve with the lower arc of the resistant hull form, and a flat upper portion.

FERRUCCIO COSSUTTA.
